OBSTETRICAL OR SIMILAR BED

Adrian Comper, Pittsfield, Mass., and Malcolm T. MacEachern, Chicago, Ill., assignors to Hospital Appliances, Inc., Pittsfield, Mass., a corporation of Massachusetts

Application February 3, 1936, Serial No. 62,212

10 Claims. (Cl. 311—7)

The invention relates principally to obstetrical beds for use in the delivery of infants, and it aims primarily to provide an unusually simple and practicable bed which will afford maximum comfort and assistance to the prospective mother, maximum convenience to the attending physician, nurse and anesthetist, and maximum insurance against confusion and delays in moving the patient from the initial at-rest position to delivery position, or to any other position which the exigencies of the case may require, for instance, to "high lithotomy" position or to "shock position".

The mattress of the bed is formed of a main section to support the patient from head to buttocks, and an auxiliary section to support the legs. The main mattress section is carried by a main mattress frame movable along a track frame, and the auxiliary mattress section is carried by an auxiliary drop frame, said main mattress frame being provided with leg supports with which the patient's legs are engaged when the delivery time nears. The drop frame and its mattress section are then lowered and the main mattress frame, main mattress section and leg-supporting means supporting the patient are bodily moved along the track frame to a delivery position at the foot end of the bed and latched in said position, placing the patient conveniently for the physician. Immediately after delivery, it is often necessary that the patient be supported in an inclined shock position, and a further object of the invention is to provide a structure in which this may be instantly and safely accomplished without moving the patient from the foot end of the bed or disturbing her in the least. In this connection, a still further aim is to provide a structure in which the main and auxiliary mattress sections may be restored to a common plane while held in an inclined position, to comfortably support the patient if it be required that she remain for a comparatively long time in shock position.

Another object is to provide for holding the main mattress section in an intermediate position between its delivery and normal positions if desired. Thus, after delivery, unless the mother must occupy the shock position, said main mattress section may be slid to said intermediate position and held, exposing a sufficient part of the auxiliary mattress section for use to support the newly born infant while giving it the necessary immediate attention.

Other objects are to provide for so supporting the drop frame that it may be rapidly, easily and

quietly lowered without in any manner disturbing the patient; to provide a structure in which said drop frame may be returned to normal position with equal dispatch; to connect the drop frame permanently with the track frame, allowing it to be raised to operative position to make the patient as comfortable as possible even if it should be necessary that said track frame and the mattress sections be left in an inclined position after delivery.

Still further objects are to make novel provision for vertically adjusting and tilting the track frame as may be required to similarly adjust or tilt the mattress sections; to provide a unique relation of tracks, rollers and frame bars for limiting the movement of the main mattress frame along the track frame; and to provide a novel base frame for the tiltable and vertically adjustable track frame which will aid the physician in case he must rather forcibly pull upon the infant, and will permit the anesthetist to conveniently follow the patient to delivery position and maintain her station at the patient's head.

With the foregoing and minor objects in view, the invention resides in the novel subject matter hereinafter described and claimed, description being accomplished by reference to the accompanying drawings.

Fig. 1 is a perspective view showing the bed adjusted to shock position.

Fig. 2 is a central vertical longitudinal section in normal position.

Fig. 3 is a central vertical longitudinal section in delivery position.

Fig. 4 is a top plan of the track frame and subjacent parts, partly in horizontal section.

Fig. 5 is a transverse section on line 5—5 of Fig. 2.

Fig. 6 is a detail vertical section on line 6—6 of Fig. 5.

Figs. 7, 8, and 9 are detail vertical sections on lines 7—7, 8—8, and 9—9 of Fig. 2.

Figs. 10 and 11 are detail horizontal sections on lines 10—10 and 11—11, of Fig. 6.

A preferred construction has been illustrated and will be rather specifically described, with the understanding however, that within the scope of the invention as claimed, variations may be made.

A base frame F of one-piece construction is provided. Upon this base frame, an elongated track frame T is mounted for vertical adjustment, not only for the convenience of the physician but to facilitate transfer of the prospective

mother from a wheeled stretcher or carrier of one height or another, to the bed, and vice versa. The track frame T is also tiltably mounted for moving the patient to "shock position" whenever 5 advisable. A main mattress-supporting frame M and an auxiliary drop frame D are both supported by the track frame T, said frame M carrying a main mattress section S to support the patient from head to buttocks and the frame D being provided with an auxiliary mattress section S' to support the legs. Carried by the frame M are leg-supporting means L which may be vertically adjusted, swung about vertical pivots or tilted upon horizontal pivots.

15 The drop frame D is mounted in such manner that it may be easily, quickly and noiselessly lowered to the position shown in Figs. 1 and 3, and the main mattress frame M is mounted for movement along the track frame T, so that after said 20 drop frame D and the mattress section S' are lowered, said frame M and the mattress section S may be moved to a delivery position at the foot end of the bed as seen in Figs. 1 and 3. Before dropping of the drop frame D and its mattress section S', the prospective mother's legs are gently lifted from said mattress section and engaged with the leg-supporting means L, permitting lowering of said frame D and mattress section S' without confusion or inconvenience and allowing 25 the patient with her legs comfortably supported, to be quickly moved to delivery position. The leg-supporting means L may be adjusted as may be required, even to "high lithotomy" position and the track frame T may be tilted as seen 30 in Fig. 1 should it be necessary to move the patient to "shock position". During such tilting, there is no danger of the frame M sliding toward the head end of the bed, due to the fact that it is held in delivery position by self-applied latches 35 hereinafter described.

Preferred features of construction will now be described, starting with the base frame F. This base frame includes parallel horizontally elongated side frames 20 disposed in vertical planes 45 and provided with brake-equipped casters 21, each of said side frames preferably comprising an arched tube 22 whose ends are equipped with the casters 21, and a longitudinal connecting tube 23 whose ends are welded or otherwise secured to the 50 end portions of the tube 22. Each side frame 20 also includes a substantially central vertical tube 24 which is welded or otherwise secured to the crown of the tube 22 and to the tube 23. At the head end of the bed, the side frames 20 are free 55 of means connecting them with each other, but at other suitable locations, transverse frame members 25, 26, 27, and 28 have been shown rigidly connecting said side frames with each other. The frame member 27 is located near the floor at 60 the foot end of the bed in such position that the attending physician can conveniently brace his feet against the same should it be necessary to pull rather strenuously upon the infant. While this bar is shown straight, it may be inwardly bowed if desired to allow the physician to stand somewhat nearer to the patient.

Two gear casings 29 are secured upon the side frames 20, said casings having openings 30 in their bottoms and openings 31 in their tops, said 65 openings 30 and 31 being vertically aligned and the openings 30 being in communication with the tubes 24. The vertical sides of the casings 29 are formed with openings 32 horizontally aligned transversely of the bed. Jack-screws 33 are received 70 in the tubes 24 and pass through the openings 30

and 31, and worm-wheels 34 within the casings 29, are threaded upon said jack-screws. A transverse shaft 35 passes through the openings 32 of the casings 29 and is provided with a hand crank or the like 36 by means of which it may be 5 rotated, and worms 37 are secured upon said shaft within the casings 29, said worms being in mesh with the worm-wheels 34.

The upper ends of the jack-screws 33 are suitably secured to horizontally elongated head blocks 10 38 and the track frame T is pivotally supported upon one end of these head blocks. Preferably a transverse pivot rod 39 passes through lugs 40 on the head blocks 38 and through openings in the side bars 41 of the track frame T to pivotally 15 mount the latter.

The ends of the head blocks 38 remote from the lugs 40 are hollow, the bottoms of these hollow end portions being formed with openings 42 and the tops thereof with openings 43. The sides of 20 these hollow end portions are formed with openings 44 aligned transversely of the bed. Bottom plates 45 are preferably secured to the head blocks 38 and are provided with vertical tubes 46 which receive vertical jack-screws 47, said jack-screws 25 passing through the openings 42 and 43 and having their upper ends operatively connected with the side bars 41 of the track frame T. Worm-wheels 48 within the hollow end portions of the head blocks 38 are threaded upon the jack-screws 30 47, said worm-wheels meshing with worms 49 in said hollow end portions. These worms are secured to a transverse shaft 50 which passes through the openings 44 and is provided with a hand wheel or the like 51 by means of which it 35 may be rotated.

Rotation of the shaft 35 by means of the crank or the like 36, elevates or lowers the jack-screws 33 and their head blocks 38 to vertically adjust the track frame T and parts carried thereby. 40 Rotation of shaft 50 by means of the hand wheel or the like 51 vertically moves the jack-screws 47 to tilt the track frame T and parts carried thereby, as may be required. The side bars 41 of this track frame are preferably of channeled form 45 with their channels disposed inwardly, and in connecting the jack-screws 47 with said side bars, we prefer to provide a construction such as that shown in Figs. 4 and 5 or of some similar nature. A transverse shaft 52 passes through 50 bearings or the like 53 at the upper ends of the jack-screws 47, said shaft being provided with rollers 54 received in the channels of the side bars 41. These rollers preferably engage the lower flanges of the side bars 41 and suitable 55 fillers such as 55 secured in the upper portions of the bar channels.

The track frame T in the present showing, consists of the two side bars 41, and two transverse bars 56 and 57 having their ends secured 60 in the channels of said side bars 41, said bars 56 and 57 being of any desired cross sectional shape. The main mattress frame M overlies the side bars 41 and is provided with brackets 58 projecting downwardly at the inner sides of said side 65 bars, said brackets being provided with rollers 59 operable in the channels of said side bars. Two of the rollers 59 are cooperable with the transverse frame bar 56 to limit the movement of the mattress frame M toward the foot end of the 70 bed, and two of said rollers coact with the frame bar 57 to limit the movement of said frame M toward the head of the bed. Frame M is held in its normal position toward the head of the bed, by abutting the drop frame D which then 75

occupies the raised position shown in Figs. 2 and 6. Suitable self-applying latches 60, however, are pivoted to the sides of the frame M to engage studs 61 on the side bars 41 of the track frame T, to hold said frame M in delivery position at the foot of the bed. These same latches 60 are engageable with other studs 61' on the bars 41 to hold the frame M in the intermediate dotted line position of Fig. 3, if desired, after the infant has been delivered. When frame M is in this position, a sufficient part of the auxiliary mattress section S' is exposed to support the newly born infant while it is receiving the attention immediately necessary.

15 The rear end of the drop frame D is pivoted at 62 to the upper ends of substantially vertical links 63 whose lower ends are pivoted to the side bars 41 of the track frame T. Preferably a transverse shaft 65 is welded or otherwise secured to the lower ends of the links 63 and the ends of this shaft are mounted in bearings 66 secured to the lower sides of the bars 41. The front end of the drop frame D is provided with short arms 67 rigidly secured thereto and projecting outwardly and downwardly, said arms 67 being engageable with the side bars 41. In the present showing, these arms are provided with portions 68 to rest upon the side bars 41 and with stud portions 69 receivable in openings 70 in said side bars. If the openings 70 be formed with bottoms, the portions 68 may be omitted. By simply lifting the foot end of the drop frame D until the studs 69 are free of the openings 70, said drop frame may be pulled away from the frame M and lowered to the position seen in Figs. 1 and 3, the inner end of said drop frame being arcuately guided by the links 63 while the arms 67 move arcuately around the foot ends of the side bars 41. The links 63, of course, support the inner end of the frame D when the latter is lowered and to support the foot end of said frame, we prefer a U-shaped hanger frame 71 whose ends are secured to the side bars 41, the frame D being notched at D' to engage said hanger frame 71.

45 It will be seen from the foregoing that novel and advantageous provision has been made for carrying out the objects of the invention. Vertical adjusting or tilting may be effected as required, the drop frame D and its mattress section 50 S' may be quickly, easily and noiselessly lowered, and the frame M, mattress section S and leg-supporting means L supporting the patient, moved forwardly over the depressed drop frame with equal dispatch, said frame M being held in 55 its delivery position by the self-applied latches 60, and later in its intermediate position by these same latches, if desired. The parts may be adjusted quickly and easily to suit the exigencies of the case and the comfort of the patient, the 60 anesthetist is not hampered by any parts of the bed, and the physician is materially assisted. Preferably, the usual anesthetist's stand 72 is pivotally connected at 73 with the head end of one of the side frames 20 and as the anesthetist 65 follows the patient to delivery position, standing or sitting unobstructedly between the head ends of the side frames 20 and the side bars 41 of the track frame T, she swings the stand toward the center of the bed for her convenience. We also 70 prefer to provide shoulder chocks 74, a sheet support 75, rings 76 for the attachment of tug straps, and lifting handles 77 for the frame D.

75 Attention is again invited to the possibility of making variations within the scope of the invention as claimed. Obviously anti-friction bear-

ings may be used throughout if desired and a number of them are indicated at 78.

We claim:

1. An obstetrical bed comprising two horizontally elongated side frames disposed in substantially vertical planes, transverse connecting means between said side frames, a substantially horizontal track frame above said side frames, means between the ends of said side and track frames supporting the latter on the former for vertical adjustment and for tilting, and mattress-supporting means associated with said track frame and including a mattress-section-carrying frame movable from a normal position at the head end of said track frame to a delivery position at the foot end thereof, said head end of said track frame being free of transverse members and said head ends of said side frames being free of transverse connecting means, permitting an anesthetist or nurse to freely enter between said side frames and occupy a position at the patient's head when said mattress-section-carrying frame is moved to delivery position. 15

2. An obstetrical bed comprising two horizontally elongated side frames disposed in substantially vertical planes, transverse connecting means between said side frames, including a bar at the foot ends of said frames against which the attending physician may brace his feet, a substantially horizontal track frame above said side frames, means between the ends of said side and track frames supporting the latter on the former for vertical adjustment and for tilting, and mattress-supporting means associated with said track frame and including a mattress-section-carrying frame movable from a normal position at the head end of said track frame to a delivery position at the foot end thereof, said head end of said track frame being free of transverse members and the head ends of said side frames being free of transverse connecting means, permitting an anesthetist or nurse to freely enter between said side frames and occupy a position at the patient's head when said mattress-section-carrying frame is moved to delivery position. 30

3. An obstetrical bed comprising a track frame, a main mattress frame slideable along said track frame and carrying a main mattress section to support the patient from head to buttocks, an auxiliary drop frame mounted on said track frame and carrying an auxiliary mattress section to support the patient's legs, two laterally spaced rigidly mounted jacks under the central portion of said track frame and having vertically adjustable upper portions to which said central 50 portion of said track frame is pivoted on a transverse horizontal axis, additional vertically adjustable jacks connecting said track frame with said upper portions of the first named jacks for tilting said track frame upon said axis, and means 55 for holding said main mattress frame against sliding on said track frame when the latter is tilted by said additional jacks. 60

4. An obstetrical bed comprising a track frame, a main mattress frame movable along said track 65 frame and carrying a main mattress section to support the patient from head to buttocks, an auxiliary drop frame separate from said main mattress frame and carrying an auxiliary mattress section to support the legs, said auxiliary 70 drop frame and auxiliary mattress section being downwardly movable with respect to said main mattress frame and section to allow movement of said main mattress frame and section to a delivery position over said auxiliary drop frame 75

- and auxiliary mattress section, longitudinally swingable links pivoted to and projecting upwardly from said track frame and also pivoted to the inner end of said auxiliary drop frame to support 5 said inner end of said auxiliary drop frame in normal raised position, said links being swingable to a position at which they hang from said track frame when said auxiliary drop frame is in lowered position, and means for supporting the outer 10 end of said auxiliary drop frame in either of said positions.
5. An obstetrical bed comprising a track frame, a main mattress frame movable along said track frame and carrying a main mattress section to 15 support the patient from head to buttocks, an auxiliary drop frame separate from said main mattress frame and carrying an auxiliary mattress section to support the legs, said auxiliary drop frame and auxiliary mattress section being 20 downwardly movable with respect to said main mattress frame and section to allow movement of said main mattress frame and section to a delivery position over said auxiliary drop frame and auxiliary mattress section, longitudinally swingable 25 links connecting the inner end of said auxiliary drop frame with said track frame to support said inner end of said auxiliary drop frame in either normal or lowered position, and lateral lugs on the foot end of said auxiliary drop frame 30 to engage the foot end of said track frame and support said auxiliary drop frame in normal position, said lugs being arcuately movable around said foot end of said track frame as said auxiliary drop frame is moved downwardly on the arcuate 35 path defined by said links.
6. An obstetrical bed comprising a track frame, a main mattress frame movable along said track frame and carrying a main mattress section to support the patient from head to buttocks, an auxiliary drop frame separate from said main mattress frame and carrying an auxiliary mattress section to support the legs, said auxiliary drop frame and auxiliary mattress section being 40 downwardly movable with respect to said main mattress frame and section to allow movement of said main mattress frame and section to a delivery position over said auxiliary drop frame and auxiliary mattress section, longitudinally swingable links connecting the inner end of said auxiliary drop frame with said track frame to support said inner end of said auxiliary drop frame in either normal or lowered position, lateral lugs on the foot end of said auxiliary drop frame 45 to engage the foot end of said track frame and support said auxiliary drop frame in normal position, said lugs being arcuately movable around said foot end of said track frame as said auxiliary drop frame is moved downwardly on the arcuate path defined by said links, and a U-shaped 50 rod secured at its ends to said track frame in position to support the outer end of said auxiliary drop frame when the latter is in lowered position.
7. In a bed of the class described, a fixed track frame comprising parallel channel-shaped track bars having their channels disposed inwardly, and at least two transverse bars between the ends of said track bars and having their ends secured in said channels, a superposed slideable frame 55 having rollers operable in said channels between said transverse bars and the ends of said track 60

bars, said transverse bars constituting stops for coaction with said rollers to limit the movements of the superposed frame along the track frame in both directions.

8. An obstetrical bed comprising a floor-supported frame, a track frame pivoted between its ends on a transverse axis to said floor-supported frame, a main mattress frame carrying a main mattress section to support the patient from head to buttocks, means slidably mounting said main mattress frame on said track frame, an auxiliary drop frame free of connection with said main mattress frame and carrying an auxiliary mattress section to support the patient's legs, means mounting said auxiliary frame in end-to-end relation with said main mattress frame and constructed to allow dropping of said auxiliary frame to a position at which said main mattress frame may slide over the same to a delivery position, releasable means for holding said main mattress frame in said delivery position, and means for tilting said track frame in a direction to raise the foot end thereof; whereby the patient supported in delivery position by said main mattress section may be quickly moved to shock position; if it be necessary to keep the patient in shock position, said main and auxiliary frames and mattress sections may be restored to end-to-end relation to comfortably support her while said track frame remains inclined; and the mattress sections may be easily restored to horizontal position when the patient's condition permits.

9. An obstetrical bed comprising two horizontally elongated side frames disposed in substantially vertical planes, transverse connecting means between said side frames, a substantially horizontal track frame at the upper portions of said side frames, means between the ends of said side and track frames tiltably supporting the latter on the former, mattress-supporting means supported by said track frame and including a mattress-section-carrying frame slideable from a normal position at the head end of said track frame to a delivery position at the foot end thereof, means for positively holding said mattress-section-carrying frame in said delivery position, and means for holding said track frame in inclined position to similarly hold said mattress-section-carrying frame if the patient must be supported in shock position.

10. An obstetrical bed comprising a floor-supported frame, a normally horizontal tilttable track frame pivoted on a transverse axis to said floor-supported frame, means for tilting said track frame and holding it in tilted position, a main mattress frame slideable on said tilttable track frame and having a main mattress section to support the patient from head to buttocks, a normally horizontal drop frame having an auxiliary mattress section normally in the plane of said main mattress section to support the patient's legs, said auxiliary mattress section and drop frame being movable to a lowered position at which said main mattress frame and section may slide thereover and means mounting said drop frame on said tilttable track frame independently of said floor-supported frame and independently of said main mattress frame.
